UNITED STATES PATENT OFFICE.

ULYSSES G. BEATTY, OF WOLF SUMMIT, WEST VIRGINIA, ASSIGNOR OF ONE-HALF
TO HERBERT KNIGHT, OF WOLF SUMMIT, WEST VIRGINIA.

CONNECTING-SOCKET.

1,034,338.

Specification of Letters Patent. Patented July 30, 1912.

Application filed February 17, 1912. Serial No. 678,280.

To all whom it may concern:

Be it known that I, ULYSSES G. BEATTY, a citizen of the United States, residing at Wolf Summit, in the county of Harrison and State of West Virginia, have invented certain new and useful Improvements in Connecting-Sockets; and I do hereby declare the following to be a full, clear, and exact description of the invention, such as will enable others skilled in the art to which it appertains to make and use the same.

This invention relates to connecting sockets used in the structural joints of metallic building structures, such as oil well derricks; and it consists of a spring socket as hereinafter fully described and claimed.

In the drawings, Figure 1 is a side view of a portion of a derrick provided with a joint socket according to this invention. Fig. 2 is a plan view of the same. Fig. 3 is a detail plan view of the socket. Fig. 4 is a side view of the socket looking at it from the opposite direction from the view shown in Fig. 1.

The socket is first formed in two pieces 2 and 3. The piece 2 is a portion of a cylinder, and is formed of a plate extending about three-quarters of a circle and having a series of lugs 4 and 5 arranged radially at each edge, and at substantially a right angle to each other.

The piece 3 is a plate extending about one-quarter of a circle, and having a series of lugs 6 and 7 at each edge, arranged to correspond with the lugs 4 and 5. All the lugs have bolt holes 8, and the tips of the lugs 4 and 6 are welded together, or are otherwise permanently secured together. The socket is formed of metal which is more or less resilient or flexible, and in its normal condition its two pieces 2 and 3 are sprung apart, as shown in Figs. 3 and 4, so that the lugs 5 and 7 are separated. A narrow converging gap 15 is formed between the main portions of the lugs 4 and 6, extending from their welded tips to the socket segments 2 and 3, and this gap is arranged radially of the socket 2. The edges of the pieces have

beveled surfaces 9 to permit free movement of one part with relation to the other.

The vertical members or tubes 10 of the derrick are placed in the end portions of the socket, with their ends in abutment against each other, when the pieces of the socket are sprung apart. Three lugs are preferably provided on each edge of each piece, but more or less than three lugs can be used. The horizontal braces 11 of the derrick are bolted to the middle lugs, and the inclined braces 12 are bolted to the top and bottom lugs. The fastening bolts 14 which pass through the holes in the lugs 5 and 7 and in the braces 11 and 12 also contract the two pieces of the socket upon the vertical members or tubes 10, so that all the said parts are firmly secured together, and no special bolts are required for clamping the socket to the tubes 10.

As the two pieces of the socket are welded together at the tips of their lugs they never get lost, and always preserve their relative positions. The exact register of the bolt holes in the lugs is assured, and the socket can be used on tubes which vary somewhat in size, as the pivotal attachment of one piece to the other by the tips of their lugs enables the curved parts of the socket to be sprung apart to a considerable extent, and without being distorted or bent out of shape.

It is not necessary that the lugs should be exactly radial of the center of the socket, and the lugs 5 are preferably arranged a little to one side of the radial line as shown in Fig. 3.

What I claim is:

In a metallic building structure, a contractible connecting socket comprising two cylindrical segments of unequal circumferential length, each segment having at its side edges a series of lugs provided with bolt holes and arranged in pairs, one series of pairs of lugs being arranged at a right angle to the other series, the adjacent surfaces of the tips of the lugs of one series being welded together beyond the bolt holes and the lugs of the other series being separated

from each other; in combination with uprights inserted in the end portions of the socket, two series of braces, and fastening bolts which secure the two series of braces to the respective series of pairs of lugs, the fastening bolts which pass through the separated lugs operating also to contract the segments upon the said uprights.

In testimony whereof I have affixed my signature in the presence of two witnesses. 10

ULYSSES G. BEATTY.
